UNITED STATES PATENT OFFICE.

ABNER JOHNSTON, OF BAINBRIDGE, ASSIGNOR TO NELSON SECOR, OF NEW YORK, N. Y.

MAIL-BAG.

SPECIFICATION forming part of Letters Patent No. 269,580, dated December 26, 1882.

Application filed September 12, 1882. (No model.)

To all whom it may concern:

Be it known that I, ABNER JOHNSTON, of Bainbridge, in the county of Chenango and State of New York, have invented an Improvement in Mail-Bags, of which the following is a specification.

The object of this invention is to provide an improved fastening for the mouths of mail-bags which shall be strong, flexible, and easily manipulated, both in opening and closing the bag; and my said invention comprises certain novel combinations of parts whereby the aforesaid objects are effectually secured.

Figure 1 is a front view, representing my said invention. Fig. 2 is a transverse vertical sectional view taken in the line xx of Fig. 1. Fig. 3 is a similar view taken in the line yy of Fig. 1. Figs. 4, 5, 6, and 7 are detached detail views of certain parts of the apparatus; and Fig. 8 is a front view, showing the upper or throat portion of the bag inverted to illustrate the manner in which the bag may be very readily opened when unlocked.

A represents a series of flat plates, which are hinged or pivoted together, as shown at a , the axes of the hinges being in the same direction as the length of the bag, while the plates themselves are arranged transversely across the flap B of the bag. Attached by rivets b to the front of the flap B are plates C, in the lower portion of each of which is a horizontal slot, c , coincident with a similar slot formed in the material of the flap itself. At the upper part of each plate C is a broad-headed screw or rivet, e . Each of the plates A, with the exception of the central one, (indicated at A^*), has at its center a vertical slot, f . The broad-headed rivet or screw e is passed through this slot in such manner that the lateral portions of the head of the rivet passing over the adjacent edges of the slot attach the plate A to the plate C in such manner that a vertical movement—that is to say, a movement in the direction of the length of the bag—is permitted to the plates A. It will be seen that the entire series of plates A, including the central one, A^* , is thus enabled to move up and down.

Each of the plates, A, except the central one, A^* , is formed with two vertical slots, g , in such

manner as to provide on each of said plates a downwardly-extended tongue, D, at or near the center of which is the vertical slot f aforesaid. This tongued portion D is re-enforced by wedge-shaped strips, as shown at h . When the series of plates A are forced upward or outward until the broad-headed rivets e are brought nearly or quite to the lower extremities of the vertical slots f the tongues D are brought clear of the horizontal slots c in the plates C and in the flap B. Secured to the upper part of the front of the bag—that is to say, over that portion of the bag upon which the flap is placed and secured when the bag is closed—are horizontal staples E, so arranged that when the flap is brought down upon the said front portion of the bag the said staples will pass upward through the horizontal slots c in the flap B and the plate C thereof and project forward beyond the outer surface of the said flaps to such an extent that when the series of plates A are brought inward the tongues D will pass into and through the staples E, and consequently secure the flap snugly upon the aforesaid front portion of the bag, the wedge-shaped re-enforces h enabling the tongues to force the flap in firm and secure contact with the said adjacent front of the bag.

The central plate, A^* , carries a catch, F, which acts in conjunction with a suitable lock, H, so that when the plates A are brought inward to attach the flap to the front of the bag, as just explained, the said catch F, passing into the lock H, will catch automatically in the internal dogs or holding devices of said lock, the latter being attached to the lower part of the flap, and thereby lock the series of plates A in their depressed condition, with the tongues D extended through the staples E, and confining the flap to the front of the bag, as hereinbefore explained.

Formed in the flap, at the upper edge of said lock, is a horizontal slot, r , and provided at the adjacent part of the upper part of the front of the bag is a staple, n , so arranged that when the flap is closed upon the said front of the bag the staple n will pass through the slot r in such position that when the catch F is forced toward and into the lock H, as just explained, the

catch F will pass under and through the said staple, thereby affording an additional hold as between the flap and the said front of the bag.

In order that the outer extremities of the plates A at the ends of the series may not be caught or injured, the said end plates are vertically slotted, as shown at 8, and shouldered studs 9 are so arranged that their lateral shoulders will extend over the adjacent edges of the slot, while the shanks of said studs passing through the slots are securely attached to the adjacent plates C.

When desired, the plate A* may be provided with a holding device, I, the internal circumference of which is grooved to receive the usual check or addressed card, which latter may be inserted through a narrow slot formed at the lower end of said holding device I and behind the catch F. Inasmuch as the series 20 of plates A, with their tongues D, are brought to and over the staples E by a movement in the direction of the length of the bag, it follows that a very slight movement of said plates is sufficient to bring the tongues D through 25 the staples E and the catch F into the lock H to securely close the bag, and that, in like manner, a slight movement only is required to bring the tongues D clear of the staples E and the catch F clear of the lock H when it 30 is desired to open the bag, this opening movement of the plates A being very readily secured by inverting the upper part of the bag—as, for example, is represented in Fig. 4—with a sudden or jerking motion, which throws the 35 said plates A and their adjuncts outward and away from the staples and locks, so that the

bag may be very readily opened after being unlocked. Furthermore, inasmuch as the plates A, including the central one, A*, are pivoted or hinged together, with their axes 40 longitudinal with the bag itself, and inasmuch as the lock is placed at the center of the top of the bag, it follows that the said upper part of the bag may be folded or bent around any axis of motion longitudinal with the bag itself 45 with very much greater facility than is the case with the mail-bag fastenings hitherto in use, this folding or bending, in the various exigencies of service, proving of very material convenience; and, furthermore, because of the 50 peculiar construction and arrangement of parts, there is no position into which a mail-bag can ordinarily be placed or thrown which will bring any severe strain upon the lock, so that the latter, as well as the other portions of the 55 fastening apparatus, are not liable to get out of order.

What I claim as my invention is—

A mail-bag fastening composed of the plates A, including the central plate, A*, hinged or 60 pivoted together on axes longitudinal with the length of the bag, and constructed with the tongues D, having wedge-like outer surfaces, the slotted plates C, the broad-headed rivets 65 e, extended through vertical slots in the plates A, suitable catch, F, and lock H, all substantially as and for the purpose herein set forth.

ABNER JOHNSTON.
